Inventor:

Paul Rauchfuss,

by Albert S. Davis
His Attorney.

UNITED STATES PATENT OFFICE.

PAUL RAUCHFUSS, OF BERLIN, GERMANY, ASSIGNOR TO GENERAL ELECTRIC COMPANY, A CORPORATION OF NEW YORK.

ELECTRIC HEATER.

Application filed November 1, 1922. Serial No. 598,403.

To all whom it may concern:

Be it known that I, PAUL RAUCHFUSS, a citizen of the German Realm, residing at Berlin, Germany, have invented certain new and useful Improvements in Electric Heaters, of which the following is a specification.

This invention relates to electric heaters, more particularly to heaters in which the liquid itself forms the heating resistance, such as used, for example, in steam boilers, and has for its object the provision of means whereby such heaters may be regulated in a simple, reliable and efficient manner.

More specifically, the heating here in question is electric heating with stationary electrodes having movable insulating tubes placed over them, in which are inserted special displacing members of insulating material. According to the invention, it is intended in the regulation of such an electric heating arrangement to effect the movement of the displacing members and of the insulating tubes by means of a common drive, this being to advantage effected in succession, and in one form of the invention being started from below by means of rack-bars, spindles, gear-wheel transmissions or the like, from a readily accessible regulating rod. By means of this form of my invention, in the lifting of the regulating rod, the displacing members are first inserted wholly in the insulating tubes, and thereafter the insulating tubes are lifted. In this way a very wide range of regulation may be obtained, and also an extremely fine and gradual regulation. In order not to interrupt suddenly, and therefore jerkily, the liquid resistance path provided above the electrodes arranged in the insulating tubes, the free ends of the insulating tubes are provided with an oblique surface of intersection with the liquid so that here also a very gradual transition is afforded.

One form of embodiment of the invention is shown by way of example of Figs. 1 and 2 of the drawing, in longitudinal section in various positions of the movable parts.

Referring to the drawing, the electrodes *a* are insulated and arranged stationarily in the boiler *b* so as to be immersed in the liquid to be heated. Over each electrode *a* is placed an insulating tube *d* which is carried by the frames *e* and *f*. The frames *e*

and *f* are held a certain distance apart by the rods *g*. Passing through the frame *e* and extending into the insulating tubes *d* are provided displacing members *h* of insulating material arranged on a common cross-piece *i* which in turn may be lifted and lowered by means of a rack-bar or spindle *k* by the cooperation of the gear-wheel transmissions *l* and *m* from the regulating rod *n*. The frames *e* and *f* for the insulating tubes *d* move on guide rods *o* passing therethrough, and their movement is limited by the stops *p* and *q* which are attached to the boiler wall. In lifting the cross-piece *i*, therefore, the displacing members *h* first enter the insulating tubes *d*, as shown in Fig. 2, and reduce the extent of the path of the liquid below the electrodes *a*. Then the cross-piece *i* engages the lower frame *e* of the insulating tubes and upon further upward movement lifts the insulating tubes themselves, as shown in Fig. 1, so that then the path of the liquid above the electrodes *a* is gradually varied. In order to cause this upper liquid path to terminate very gradually, the upper free ends of the insulating tubes *d* are provided with oblique sectional surfaces *r*.

In letting down the cross-piece *i*, the insulating tubes *d*, together with their frames *f* and *e* at first slide downward until they rest on the stops *p* and *q*, after which the cross-piece *i*, together with the displacement members *h*, moves farther downward so that the displacing members gradually slide out of the insulating tubes *d*.

What I claim as new and desire to secure by Letters Patent of the United States, is:—

1. An electric heater for liquids comprising a plurality of electrodes immersed in the liquid to be heated, a movable insulating tubular member surrounding one of said electrodes, a movable displacing member cooperating with said tubular member, and a common means for moving said members so as to vary the liquid paths through said tubular member.

2. An electric heater for liquids comprising a plurality of electrodes immersed in the liquid to be heated, a movable insulating tube surrounding one of said electrodes, a movable insulating displacing member cooperating with the lower end of said tube, and a common actuating device arranged to

lift said member and said tube so as to vary the liquid paths through the ends of said tube in succession.

3. An electric heater for liquids comprising a plurality of electrodes immersed in the liquid to be heated, upright movable insulating tubes surrounding said electrodes, movable insulating displacing members adapted to be inserted in the lower ends of 10 said tubes, and a common actuating device arranged to lift first said displacing members and then said tubes so as to vary the liquid paths in succession through the lower and upper ends of said tubes.

4. An electric heater for liquids comprising a plurality of electrodes immersed in the liquid to be heated, movable insulating tubes surrounding said electrodes, the upper ends of said tubes being oblique, movable 20 insulating displacing members adapted to be inserted in the lower ends of said tubes, a common actuating device arranged to lift first said displacing members into said tubes and then said displacing members and said tubes together so as to vary the liquid paths in succession through the lower and upper ends of said tubes.

5. An electric heater for liquids comprising a plurality of electrodes immersed into 30 the liquid to be heated, a plurality of insulating tubes surrounding said electrodes and providing upper and lower heating paths between said electrodes through the

upper and lower ends of said tubes respectively, the upper ends of said tubes being 35 oblique, displacing members adapted to be inserted in the lower ends of said tubes, and a common actuating device for lifting said displacing members into said tubes so as to regulate said lower heating path, and then 40 lifting said displacing members and said tubes together so as to regulate said upper heating path.

6. An electric heater for liquids comprising a plurality of electrodes immersed in 45 the liquid to be heated, a plurality of upright insulating tubes surrounding said electrodes, the upper ends of said tubes being 50 oblique, a support for said tubes mounted for movement in a vertical direction, displacing members adapted to be inserted in the lower ends of said tubes, a support for said displacing members adapted to engage the support for said tubes after said displacing members have been lifted into said 55 tube, and actuating mechanism for said displacing member support extending without the boiler, whereby said displacing members may be lifted to vary the liquid path through the lower ends of said tubes, after 60 which said tubes may be lifted with said displacing members to vary the liquid paths through the upper ends of said tubes.

In witness whereof, I have hereunto set my hand this 9th day of October, 1922.

PAUL RAUCHFUSS.
